[57] CLAIM

The ornamental design for an arm chair protector, as shown and described.

DESCRIPTION

FIG. 1 is a perspective view of the arm chair protector positioned on a chair showing our new design;

FIG. 2 is a perspective view of the arm chair protector.

FIG. 3 is a front view thereof.

FIG. 4 is a back view thereof.

FIG. 5 is a side view thereof, the opposite side view being symmetrical.

FIG. 6 is a top view thereof; and,

FIG. 7 is a bottom view thereof.

Dashed lines indicate stitched seams. The arm chair shown with broken lines in FIG. 1 illustrates an environmental structure and does not form part of the claimed design.
